(57) **CLAIM**

The ornamental design for a string trimmer bubble toy, as shown and described.

DESCRIPTION

FIG. 1 is a side perspective view of the string trimmer bubble toy showing our new design;

FIG. 2 is a right side view thereof;

FIG. 3 is a left side view thereof;

FIG. 4 is a top plan view thereof;

FIG. 5 is a bottom plan view thereof;

FIG. 6 is a rear view thereof; and

FIG. 7 is a front view thereof; and,

FIG. 8 is a side perspective view thereof showing the toy in a collapsed configuration.

The broken lines shown in the drawings depict environment and form no part of the claimed design.
